United States Patent Office.

WILLARD L. STARLIN, OF BENWOOD, WEST VIRGINIA.

Letters Patent No. 86,327, dated January 26, 1869.

IMPROVED TUYERE.

The Schedule referred to in these Letters Patent and making part of the same.

To all whom it may concern:

Be it known that I, WILLARD L. STARLIN, of Benwood, in the county of Marshall, and in the State of West Virginia, have invented certain new and useful Improvements in Tuyere-Irons; and do hereby declare that the following is a full, clear, and exact description thereof, reference being had to the accompanying drawings, and to the letters of reference marked thereon.

The nature of my invention consists in the construction and general arrangement of a tuyere-iron, which will be hereinafter fully set forth.

In order to enable others skilled in the art to which my invention appertains, to make and use the same, I will now proceed to describe its construction and operation, referring to the annexed drawings, which form a part of this specification, and in which—

Figure 1 is a side view;

Figure 2 is a longitudinal vertical section;

Figure 3 is a transverse section of the end nearest the bellows; and

Figure 4 is a transverse section of the end nearest the fire.

I construct my tuyere-iron of two parts, A and B.

The part A is in the shape of a tapering cylinder, of suitable size, open at the larger end, but partially closed at the smaller end; that is, forming a solid end, with an opening or aperture in the centre.

A pipe, C, leads from this opening back through the centre of the cylinder, ending a suitable distance from the open end of the same.

The cylinder A and pipe C may be cast in one piece, which is decidedly preferable to making them in several parts, and then joining them together.

The part B of the tuyere-iron forms an air-chamber, D, with an opening, E, which is connected with the bellows, and is placed over the open end of the cylinder A, and secured to the same by set-screws F F, or any other suitable means, so as to make the joint perfectly air-tight.

From the air-chamber D, one, two, or more tubes, I I, lead into the circular chamber formed between the sides of the cylinder A and pipe C, and extend to within a short distance from the closed end of said cylinder.

The air, as it is forced into the air-chamber D from the bellows, passes through the pipes I I, thence back again to near the outside of the air-chamber D, when it enters the pipe C, and is communicated to the fire.

By this arrangement, a constant current of cold air is kept, at all times, on the inside of the end near the fire, cooling it, instead of the usual trouble to cool it with water.

Having thus fully described my invention,

What I claim as new, and desire to secure by Letters Patent, is—

The combination of the cylinder A, tube C, cap B, with opening E and air-chamber D, from which extend two or more pipes, I I, into the cylinder A, all substantially as herein shown and described.

In testimony that I claim the foregoing, I have hereunto set my hand, this 23d day of November, 1868.

WILLARD L. STARLIN.
